UNITED STATES PATENT OFFICE.

E. L. HAGAR, OF FRANKFORT, NEW YORK, ASSIGNOR TO HIMSELF AND T. D. AYLSWORTH,
OF ILION, NEW YORK.

MACHINE FOR WRINGING CLOTHES.

Specification of Letters Patent No. 20,470, dated June 1, 1858.

To all whom it may concern:

Be it known that I, EDWIN L. HAGAR, of Frankfort, in the county of Herkimer and State of New York, have invented a new 5 Machine or Apparatus to Assist in Wringing Clothes at the Wash-tub; and I do hereby declare that the following is a full and exact description thereof, reference being had to the accompanying drawings and the letters 10 of reference made thereon.

The nature of my invention consists in providing a self-acting clasp which is attached to the rim or edge of the tub which receives and holds one end of the article to be 15 wrung, while with the two hands twisting in one direction the article is wrung to great advantage.

To enable others skilled in the art to make and use my invention I will proceed to describe its construction and operation.

Figure 1, of the annexed drawings represents the wash-tub with my apparatus attached to it as when in use. A, is the tub, B, the clasp, and C an article of clothing as 25 when in the operation of wringing. B, Fig. 2, is a separate view of the clasp on a scale enlarged to about one half the working size. It consists of a wooden stock D, to which are attached the crooked wire hooks α , α . These 30 hooks are made of brass or other metal that will not be easily corroded so as to mark the clothes. They are both of one piece of wire which passes through the stock by the orifice e , in which the wire works easily.

To prepare the tub for the use of the clasp, it is simply necessary to insert two small staples, about two inches below the rim of the tub, outside as at f . These are for the 35 reception of the hooks α , α , Fig. 2, and they are in a position to be reached by these hooks when the horizontal part of the wire of the hooks is slightly let into the rim of the tub to keep the clasp steady. When in use on the tub the clasp occupies the position shown 40 in the drawings, but it is attached to the tub by turning the upper end downward outside the tub, and inserting the hooks α , in the

staples above mentioned, and then with the hooks so inserted bringing the clasp over, reversing the position of the ends, and bringing the clasp to the position shown in the figure, (Fig. 1.) The hooks are thus securely fixed in the staples and will safely hold the clasp when in use. The staples outside the tub at f , are not seen in the drawing but will be readily understood from the description. C, (Fig. 1,) represents an article of clothing in position as when the water is being wrung from it over the tub.

The manner in which the clasp is made to hold one end of the article while in the act of wringing is shown at i . The article to be wrung, at the point at which it is desired that the clasp should seize it is laid horizontally within the space g , (Fig. 2,) between the post h , and the movable wire E, the left-hand end hanging down as seen at k . The post at the right is then brought back outside of and around the wire and being drawn up the wire is brought up with it clasping 70 the clothes between the wire and post so that the draft or tension upon the clothes C, (Fig. 1,) grasps the article more closely and holds it securely. Any other mode of fastening the clothes to the clasp may be adopted, but the process described is simple and quickly performed.

The point of holding upon the article may be quickly changed at will, until all its parts are sufficiently wrung. The clasp may be 75 used on any tub or box containing the clothes to be washed and may be easily removed, and again replaced at pleasure.

What I claim as new, and desire to secure by Letters Patent is—

The clasp B, and its attachment and adjustment to the tub as described and shown, the whole being arranged and operating substantially in the manner and for the purpose herein set forth.

EDWIN L. HAGAR.
